UNITED STATES PATENT OFFICE

166,296

LIGHTING FIXTURE WALL BRACKET

John W. Brooks, Syracuse, N. Y.

Application January 15, 1951, Serial No. 13,812

Term of patent 14 years

(Cl. D48—4)

To all whom it may concern:

Be it known that I, John W. Brooks, a citizen of the United States, residing at Syracuse, in the county of Onondaga and State of New York, have invented a new, original, and ornamental Design for Lighting Fixture Wall Bracket, of which the following is a specification, reference being had to the accompanying drawing, forming a part thereof, and in which

Fig. 1 is a front elevation of a lighting fixture wall bracket, showing my new design;

Fig. 2 is a bottom plan view thereof;

Fig. 3 is a side elevation thereof; and

Fig. 4 is a top plan view thereof.

The dotted lines shown in the drawing are for illustrative purposes only.

I claim:

The ornamental design for a lighting fixture wall bracket, substantially as shown and described.

JOHN W. BROOKS.
